UNITED STATES PATENT OFFICE

164,055

DOOR FOR A REFRIGERATOR CABINET

Oscar E. Norberg and Alfred E. Nave, Cincinnati, Ohio, assignors to Avco Manufacturing Corporation, Cincinnati, Ohio, a corporation of Delaware

Application October 19, 1949, Serial No. 5,569

Term of patent 14 years

(Cl. D67—3)

To all whom it may concern:

Be it known that we, Oscar E. Norberg and Alfred E. Nave, both citizens of the United States, residing at 2720 McKinley Avenue and 3134 Queen City Avenue, Cincinnati, Ohio, respectively, in the county of Hamilton, have invented a new, original, and ornamental Design for a Door for a Refrigerator cabinet of which the following is a specification, reference being had to the accompanying drawing, forming a part hereof.

In the drawing:

Fig. 1 is an elevation of the rear of a door for a refrigerator Cabinet, showing our new design.

Fig. 2 is a side elevation thereof.

Fig. 3 is a sectional view taken along line 3—3 of Fig. 1.

The side of the door not disclosed is substantially plain and similar to the side shown. The front of the door, not shown, is substantially plain.

The dominant features of our design reside in the portions shown in full lines.

We claim:

The ornamental design for a door for a refrigerator cabinet, substantially as shown and described.

OSCAR E. NORBERG.
ALFRED E. NAVE.
